(12) **United States Design Patent** (10) Patent No.: **US D884,664 S**
(45) Date of Patent: **** May 19, 2020**

(54) **FLEXIBLE ELECTRONIC DEVICE**

(71) Applicant: **Lenovo (Beijing) Co., Ltd.**, Beijing (CN)

(72) Inventor: **Jincherl Kwon**, Beijing (CN)

(73) Assignee: **Lenovo (Beijing) Co., Ltd.**, Beijing (CN)

(**) Term: **15 Years**

(21) Appl. No.: **29/697,213**

(22) Filed: **Jul. 5, 2019**

Related U.S. Application Data

(62) Division of application No. 29/639,255, filed on Mar. 5, 2018, now Pat. No. Des. 859,347, which is a division of application No. 29/562,445, filed on Apr. 26, 2016, now Pat. No. Des. 814,435.

(57) **CLAIM**

The ornamental design for a flexible electronic device, as shown and described.

DESCRIPTION

FIG. 1 is a perspective view of a flexible electronic device showing the new design;

FIG. 2 is a front view thereof;

FIG. 3 is a back view thereof;

FIG. 4 is a left side view thereof;

FIG. 5 is a right side view thereof;

FIG. 6 is a perspective view of the new design shown in a first bending position;

FIG. 7 is a left side view of FIG. 6;

FIG. 8 is a perspective view of the new design shown in a second bending position;

FIG. 9 is a left side view of FIG. 8;

FIG. 10 is a perspective view of the new design shown in a third bending position;

FIG. 11 is a left side view of FIG. 10; and,

FIG. 12 is another perspective view of the new design shown in a third bending position.

The features shown in broken lines in the drawings depict environmental subject matter and form no part of the claimed design.
